UNITED STATES PATENT OFFICE.

OTTO MAYER, OF AMERICAN FALLS, IDAHO.

COIN-CONTROLLED LOCKER.

1,077,846.

Specification of Letters Patent.

Patented Nov. 4, 1913.

Application filed May 8, 1912. Serial No. 695,945.

To all whom it may concern:

Be it known that I, OTTO MAYER, a citizen of the United States, residing at American Falls, in the county of Oneida and State of Idaho, have invented new and useful Improvements in Coin-Controlled Lockers, of which the following is a specification.

This invention relates to coin-controlled lockers, the object in view being to provide a locker suitable for containing articles of clothing, or a dress-suit case or the like, and embodying in connection with a lock for fastening the door of the locker, coin controlled means, by which the key which operates the lock may only be removed therefrom upon depositing a coin of the required value therein. The door may be unlocked by simply inserting the key at any subsequent time, but thereafter the key may be held securely and prevented from being again withdrawn, until another coin is deposited in the slot provided therefor.

With the above and other objects in view, the invention consists in the construction, combination and arrangement of parts, as will be hereinafter more fully described, illustrated in the accompanying drawings, and pointed out in the claims hereunto appended.

In the drawings: Figure 1 is a front elevation of a locker, showing the door thereof thrown open and illustrating the coin-controlled mechanism of this invention, preparatory to the insertion of a coin. Fig. 2 is an inside face view of the door, showing the position assumed by the mechanism, after the insertion of the coin. Fig. 3 is a detail view of the key. Fig. 4 is a detail vertical section through the lock mechanism.

Referring to the drawings, 1 designates a box-like locker of any desired size, according to the use to which the locker is to be put. This locker is adapted to contain such articles of clothing as hats, coats, overcoats, and the like, or a dress-suit case containing articles of wearing apparel.

This locker is provided with a hinged door 2, upon which is placed a suitable lock 3 adapted to be operated by means of a key, embodying a shank 4, a handle 5, and bit 6. In order to carry out the present invention, the shank of the key is enlarged to form a wedge or cone-shaped spreader 7, terminating in an abrupt transverse shoulder 8, by means of which the

key is held fastened in the lock 3 on the door of the locker, in the manner as will herein-after appear.

Arranged in opposite sides of the key hole 60 are sliding latches 9, mounted in suitable guides 10 and having their inner ends concaved to embrace the shank 4 of the key and rest back of the shoulder 8 of said key.

At their outer ends, the sliding latches 65 9 are connected to levers 11 which are pivotally mounted, at 12, on the door and connected by a contractile spring 13 which serves to hold the latches normally in engagement with the key.

Above the mechanism just described, is arranged a plunger 14 having at a suitable point in the length thereof, a shoulder 15. This plunger extends above the top of the door, where it is provided with an operating knob or button 16, the plunger being normally upheld by means of a coiled spring 17.

At its lower end, the plunger is pivotally connected, at 18, to a pair of oppositely arranged elbow levers 19 provided at their lower ends with hook-shaped projections 20 adapted to engage shoulders 21 on the latches 9 for moving said latches out of engagement with the key.

The plunger is normally held locked at the upper limit of its movement by means of a pawl 22 pivoted on the door, as shown, and connected by a link 23, such as a piece of wire, to a coin-operated lever 24, one end 90 of which lies in a vertical coin chute 25, the upper end of which opens out in a slot 26 at the top of the door, while the lower end thereof communicates with a coin receptacle 27 arranged on the inner side of the door 95 and near the bottom thereof.

In order to restore the pawl 22 to its locking position with reference to the plunger 14, I provide a pawl replacing lever 28 which is fulcrumed, at 29, and has the extremity thereof arranged in the path of the plunger 14, so that as the plunger is depressed, the lever 28 comes into contact with the pawl 22 and moves the same back into engagement with the plunger to prevent further depression of said plunger.

In operation, the key being held in the lock by the latches 9, a coin is dropped into the slot 26, and in falling it comes into contact with the lever 24. This acts, through the link 23, to move the pawl 22 out from under the shoulder 15 of the plunger 14.

The operator now presses down on the plunger, and thereby thrusts the latches 9 out of engagement with the key, so that after the door of the locker is locked, the key 5 may be withdrawn therefrom.

In order to unlock the device, the key is thrust into the lock, and the tapered or wedge-shaped portion 7 thereof serves to spread apart the latches 9, which subsequently spring inwardly behind the shoulder of the key and lock the same therein. This 10 enables the door to be unlocked, and the contents thereof recovered, but it is impossible to again remove the key, until another coin has been deposited in the slot provided 15 therefor.

What is claimed is:

1. The combination with the door of a locker, of lock mechanism, a key for operating 20 the lock mechanism, said key being provided with a tapering or wedge-shaped portion and a transverse shoulder, a pair of oppositely arranged latches coöperating with said key, means for yieldingly urging said

latches toward the key, a plunger, and connections between said plunger and the latches for moving the latches out of engagement with the key, and means for holding and releasing said plunger. 25

2. The combination with the door of a 30 locker, of a key for operating the lock thereof, said key being provided with a tapering or wedge-like portion, and a shoulder at one end thereof, oppositely arranged sliding latches movable toward and away from the 35 key, a spring for urging said latches toward the key, oppositely arranged elbow levers arranged to move the latches out of engagement with the key, a plunger connected to said levers for simultaneously operating 40 them, and means for holding and releasing said plunger.

In testimony whereof I affix my signature in presence of two witnesses.

OTTO MAYER.
